Primary Examiner — Darlington Ly(74) *Attorney, Agent, or Firm* — Norton Rose Fulbright Canada LLP(57) **CLAIM**

The ornamental design for a drainage device for a vehicle, as shown and described.

DESCRIPTION

FIG. 1 is a perspective view of the drainage device for a vehicle showing our new design;

FIG. 2 is a front elevation view thereof;

FIG. 3 is a right side elevation view thereof, to which the left side elevation view is a mirror image;

FIG. 4 is a rear elevation view thereof;

FIG. 5 is a top plan view thereof; and,

FIG. 6 is a bottom plan view thereof.

The drainage device for a vehicle is shown with a symbolic break in its length. The appearance of any portion of the drainage device for a vehicle between the breaks do not form part of the claimed design.
